UNITED STATES PATENT OFFICE

FRANK N. ROEHRICH AND ALEX LEVINE, OF JERSEY CITY, NEW JERSEY; SAID ROEHRICH ASSIGNOR TO SAID LEVINE

ARTICLE DISPENSING APPARATUS

Application filed July 9, 1929. Serial No. 377,062.

This invention relates to an apparatus for dispensing merchandise and automatically registering or indicating the removal of each succeeding article, which apparatus is particularly, though not exclusively, designed for use in connection with retail sales of articles of relatively-high cost, such for example, as radio tubes.

The principal object of our invention is to provide an apparatus having a manually-operative delivery element by means of which articles may be consecutively withdrawn from a magazine to a position for convenient removal, and having also indicating or registering mechanism which is positively actuated as and when the delivery element, minus the presented article, is returned to its receiving position with relation to the magazine, the construction and operation being such that the said indicating or registering mechanism remains inactive if the delivery element with the article imposed thereon should be returned to its receiving position in respect to the magazine. Hence, if the article when presented by the delivery element should be removed therefrom and the element then be returned to its receiving position, the absence of the article will be indicated or registered, but if, on the other hand, preparatory to the return of the element to its receiving position, the article should be allowed to remain on the delivery element, or should be removed and replaced thereon, no removal or sales indication will be effected. Consequently provision is had whereby an efficient check on articles actually removed from and not returned to the magazine is ensured.

With this and other objects in view our invention embodies novel features of construction and operation, and combinations of parts which will be hereinafter described; the scope of the invention then being defined in the appended claims.

In the drawings—

Figure 1 is a side elevation of an apparatus embodying the principle of our invention, the base being in section and the delivery mechanism being shown in closed or article receiving position.

Fig. 2 is a transverse vertical section

through the apparatus, as on the line 2—2 of Fig. 1.

Fig. 3 is a view similar to Fig. 1, but showing the delivery mechanism in its outward or delivery position, preparatory to the removal of the presented article.

Fig. 4 is a view similar to Fig. 3, from the opposite side of the apparatus, showing the parts in their relative positions after the removal of the article and immediately before the inward or closing movement of the delivery mechanism.

Figs. 5, 6 and 7 are transverse horizontal sections, as on the lines 5—5; 6—6 and 7—7, respectively, of Fig. 3.

Fig. 8 is a transverse horizontal section of the apparatus, immediately above the base, as on the line 8—8 of Fig. 1.

Fig. 8^a is a vertical section through the front plate structure of the carriage, as on the line 8^a—8^a of Fig. 3.

Fig. 9 is a perspective view of the "restocking" indicator.

Figs. 10, 11 and 12 are skeleton perspective views of locking and unlocking devices for the delivery mechanism, showing such devices in different relative positions which they are caused to assume.

Fig. 13 is a perspective of a rearward locking pawl and co-operating devices therefor.

Fig. 14 is a sectional elevation of the cam and lever mechanism for actuating and controlling the operation of a vertical reciprocating register controlling element which is included in the delivery mechanism.

Fig. 15 is a transverse vertical section, as on the line 15—15 of Fig. 14.

Fig. 16 is a fragmentary plan of latch controlling devices for the register controlling element.

Fig. 17 is a longitudinal vertical section, as on the line 17—17 of Fig. 16.

Fig. 18 is a partial front elevation of an apparatus equipped with a series of independent delivery mechanisms, each embodying the invention.

Figs. 19, 20, 21 and 22 are sectional elevations illustrating counting and registering mechanism and operating devices therefor, which devices are shown in succeeding po-

sitions that they are caused to assume at different intervals of operation of the delivery mechanism.

Referring to the drawings, 25 designates a supporting framework of suitable shape and size for its intended purpose. In the present instance this framework is a skeleton structure including a rectangular base frame having upstanding corner posts 26 to which side casing panels may be secured. The base includes a pair of parallel longitudinally slotted bars 27 extending from side to side of the base. Upon these bars are supported at the front of the framework a series of vertical magazines, each of which is designed to contain a stack of cartons C of uniform size, the lowermost carton being supported a suitable distance above the base. Each of the magazines includes front and rear pairs of vertical bars 28, 29, respectively, rising from a pair of spaced longitudinally slotted cross-bars 30 having angle pieces 31 which extend transversely of and rest upon the slotted base bars 27. The angle-pieces are secured in place by means of bolts 280 passing through the slots 290 of the bars 27, and hence by proper manipulation of the bolts the bars 30 can be released and the magazine adjusted longitudinally of the frame base 27 and then secured in proper position, as occasion may require, or either or both pairs of bars can be adjusted toward or from each other to accommodate cartons of different widths. The rearward bars 29 of the magazine are secured in place by bolts 32 passing through the slots 33 of the cross-bars 30, so that by proper manipulation of the bolts 32, the bars 30 can be released and adjusted toward or from the front bars, and then secured in proper position to accommodate cartons of different length. The front of the framework 25 is equipped with hinged doors 34 which may be opened for access to the magazines, or any of them, as need may require, which doors are preferably provided with glass panels 35 through which the contents of the magazines may be observed. (See Figs. 8 and 18.)

Each of the magazines constitutes a preferred form of means whereby articles are successively supplied to manually operative article delivery mechanism hereinafter described.

Located in the space beneath each of the magazines is a stationary frame structure which extends from the front to the back of the base, which structure preferably includes a pair of spaced parallel side plates 36, and also a base plate 37 which rests upon the slotted cross-bars 27 of the supporting frame base. The base plate 37 is secured in place by bolts 38 passing through the slots 290 of the bars 27, and hence by proper manipulation of the bolts 38 the stationary frame can be adjusted longitudinal-

ly of the main frame base, correspondingly with the magazine, and then secured in place.

Movably mounted in the stationary frame structure below and transversely of the magazine, is a carriage containing manually-operative mechanisms, which, in the movements of the carriage, effect the withdrawal of each succeeding lowermost carton from the magazine, which mechanisms include a vertically movable register controlling element, which determines the operative position of a trip element of a counter or registering mechanism when any article is withdrawn from the magazine and not returned thereto, as will be presently explained.

The carriage, in its preferred construction, includes a front end portion 39 affixed to a vertical plate 390 to which is fastened a rectangular face plate 40 of suitable shape and size to close the front of the space below the adjacent magazine. Extending inwardly from the plate 390, about the midsection thereof, is a horizontal longitudinally slotted bar 400 which is fitted in guides 41 in the sides of the stationary frame. (See Figs. 2, 3 and 4). The forward plate 390 has secured thereto a longitudinally slotted horizontal shelf plate 44 which extends in a plane above the bar 400, the relative positions of the parts being such that when the carriage is in its inward position, the unslotted portion of the shelf plate 44 adjacent the forward plate 390 lies directly under the magazine and affords a support for the lowermost carton of the superposed stack. (See Fig. 1).

The shelf plate is mounted on the plate 390 so as to be vertically adjustable to accommodate cartons of different heights. Accordingly the forward end of the shelf plate is provided with a bend or flange 410 which is secured to the plate 390 by means of a bolt 420 passing through a vertical slot 421 in the latter plate. (See Figs. 1, 2 and 3).

Vertical side extension plates 430 for the front plate 40 are slidably fitted between the latter and the plate 390, so as to be laterally adjustable correspondingly with the adjustment of the magazine standards 28, 29. The extension plates have affixed thereto, about the middle thereof, a series of spaced cross-bars 440, whereof the bars of one plate overlap the other plate and are slidably fitted between fixed guide bars 441 on the plate 390, thus ensuring the support and guidance of the extension plates. (See Fig. 8.) Preferably the extension plates are provided adjacent their respective ends with similar cross-bars 442 which overlap the respective plates and contribute to their support and guidance. These extension plates, which are clamped in their positions of adjustment by screws 450 connecting the plates 390, 40, support near their tops, parallel lateral guide

rails 42 which extend inward and are slideable in horizontal guide bars 43 on the adjacent vertical standards 28, 29, below the magazine. Thus the guide bars 43 are laterally adjusted by and with the plates 430 to accord with the spaced relation of the standards 28, 29. In the present instance the forward ends of the bars 43 are formed with angle bends which are engaged with up-standing tongues 450 on the respective plates 430.

10 The vertically-movable register controlling element, which, is mounted on and movable horizontally with the carriage, comprises a T-shaped body, whereof the horizontal top bar lies some distance below the top of the article supporting shelf when the element is in its down position, as seen in Fig. 4. This top bar terminates in a depending forward member 45 which is spaced a suitable distance inwardly from the front plate 390 to permit the member to be moved vertically back of and close to the carton supported on the shelf. The top bar is preferably made in two sections, whereof the forward section 46, embodying the member 45, is adjustable toward or from the front of the magazine correspondingly with the adjustment of the rear bars 29. To this end, the rearward section 47 is longitudinally slotted vertically, as at 48, to receive the tail of the forward section, and is horizontally slotted, as at 49, to receive securing screws or bolts 50. (See Figs. 3 and 5.)

15 The lower end of the vertical leg 51 of the element is pivotally connected, as at 52, to the lower ends (Fig. 1) of two corresponding pairs of inclined parallel links 53, the upper forward ends of which links are, in turn, pivoted, as at 54, to and between depending ears 55 at the forward ends of the bars 400, the lower ends of which pair of links are provided with suitable space blocks 56. The lower block is formed with a depending arm 57 which is connected by means 20 of a link 58 with the lower end of a pendant vibratory arm 59 which is pivoted, as at 60, to and between ears 55. The arm is equipped with a roll 61 which bears against the cam surface 62 of a cam wheel 63 fast on a horizontal shaft 64 having its bearings in the plates 390, 40, said shaft and cam wheel being rotatable through an arc of 180°. (See Figs. 14, 15). The cam wheel is provided with a radial stud 65 which co-acts with suitably-located stops 66 to determine the limits of rotation of the shaft 64. The free end of this shaft projects beyond the front plate 40 and is provided with a suitable handle 67 to facilitate the manual operation of the shaft 25 and also the outward and inward movements of the carriage and its appurtenances. The weight of the register controlling element 51 etc., plus that of the inclined links, tends to maintain the roll 61 in operative contact with the cam surface 62, the contour of which sur-

face is such as to effect by the partial rotation of the cam wheel 63 in one direction the positive vertical raising of the register controlling element through the medium of the lever and link connections, in which position it may be temporarily locked, and to permit by a reverse movement of the cam wheel the descent of the register controlling element if the latter be unlocked. (See Figs. 1, 3, 4, 14 and 15). ⁷⁰ ~~and for some of said connections~~ ⁷⁵

20 Journaled in suitable bearings on the front portion 390 of the carriage and in a bracket 68 depending from the rear of the carriage bar 400 are the respective ends of a shaft 69 which lies below and parallel with the axial plane of the shaft 64. The shaft 69, throughout the greater part of its length is square, or other polygonal form, in cross-section, as at 70. (See Fig. 7). Fixed to one of the side members 36 of the stationary frame is a bracket 71 having an opening 72 which corresponds with the polygonal form of the shaft 69, and is so located that when the carriage is in its inward position, as seen in Fig. 1, the forward round portion of the shaft ⁸⁰ ₉₀ extends therethrough, and that when such structure is in its outward position the rearward round portion of the shaft extends through the opening, as seen in Figs. 3 and 4, thus permitting semi-rotation of the shaft ⁹⁵ when the carriage is at either limit of its longitudinal path of movement. In the longitudinal movement of the carriage the polygonal portion of the shaft travels in the opening 72, thus preventing rotative motion of ¹⁰⁰ the shaft. The forward end of the shaft 69 and the adjacent end of the shaft 64 are provided with co-acting gears 73, 74, respectively, whereby when the handle 67 of the latter shaft is properly turned, at either limit of travel of the carriage, the motion is transmitted to the shaft 69, and at the same time the longitudinal backward or forward travel of the carriage, as the case may be, can be effected unless such travel be restrained by ¹⁰⁵ suitable locking devices. (See Figs. 1, 3 and 4). The locking devices herein shown, include a peripherally notched disk 75 which is affixed to the rearward portion of the shaft 69, and is adapted to be engaged by two relatively fixed locking dogs 76, 77 located respectively in the vicinity of the rearward and forward positions of the disk 75. ¹¹⁵

25 The rearward dog 76 is pivoted, as at 78, to one side of the stationary frame and has in its upper edge a vertical notch 79 at the base of an inclined nose portion 80. This dog is resiliently supported in the path of the lower edge of the disk 75 by a suitably-disposed spring 81, and is so located that as ¹²⁰ the carriage approaches its rearward limit of travel the disk rides upon and depresses the nose of the dog until the disk reaches the notch, 79, whereupon the dog snaps upward and engages the disk, as seen in Fig. 10. The ¹²⁵ ₁₃₀

notch 800 in the disk is so located that when the shaft 64 is partially turned by a counter-clockwise movement of the handle 67 the notch registers with the under edge of the dog, as seen in Fig. 11, thus freeing the disk from the locking effect of the dog and permitting the carriage to be pulled forward by means of the handle, as in Figs. 3 and 4.

The forward dog 77 is pivoted, as at 82, to a bracket 83 fast to one of the side bars 36 of the stationary frame and has in its under edge a notch 84 adjacent an inclined portion 85. This dog normally gravitates into the path of the upper edge of the disk 75 and is so located that as the carriage approaches its forward limit of travel the disk rides under and raises the opposing dog until the disk reaches the notch 84, whereupon the dog descends and engages the disk, as seen in Fig. 3. 15 When the shaft 64 is properly turned by a clockwise movement of the handle 67 the notch 800 of the disk registers with the notch 84 of the dog 77, as seen in Fig. 4, thus freeing the disk from the locking effect of the 20 dog and permitting the carriage to be pushed rearward, as in Fig. 1.

Mounted in a suitable bearing in the rear of the carriage bar 400 is a vertical shaft 86 to which is affixed a radial latch arm 87 operable, by proper rotative movement of the shaft, to be swung under or from the lower end of the leg 51 of the register controlling element when such element is in raised position. A torsional spring 88 encircling the 25 shaft 86 and having one end secured to the bracket 68 and the other end extending into an aperture in the latch arm, tends normally to maintain the shaft with its latch arm in locking position. (See Fig. 17.)

Fast on the upper end of the shaft 86 is a head 89 having two spaced up-standing lugs 90, 91. The lug 90 constitutes a crank member actuatable to effect the movement of the shaft to set the latch arm 87 temporarily in 30 unlocking relation to the leg 51, and the other lug 91 co-acts with a suitably-disposed latch rod 92 to lock the shaft 86 with its latch arm in outer or releasing position against the action of the spring 88, if and when the lowest carton is withdrawn from the stack and removed from the machine, as will be hereinafter described.

The angular relation of the crank lug 90 to the axis of the shaft 86 is such that as the carriage approaches the limit of its rearward travel the lug passes under the latch head 93 of a dog 94 which is pivoted, as at 95, to one side 36 of the stationary frame. (See Figs. 1 and 10.) The corner of the lug 90 adjacent the latch head is inclined or bevelled, as at 96, so as to co-act with the depending nose of the latch head 93 to effect the partial turning of the crank head 89 and its shaft 86 in a manner to set the latch arm 87 in outer or unlocking 45 relation to the leg 51. On the lower part of

the shaft 86 is a laterally projecting stud 97 which is adapted to be engaged by a spring-pressed notched dog 98 when the latch arm 87 is swung outward, thus locking the arm 87 in outer position. This dog is pivoted, as at 99, 70 on the depending bracket 68 of the carriage bar 400, and is provided with a laterally extending toe 100 under which rides, at the limit of the semi-rotation of the shaft to unlock the disk 75 from the forward dog 77, a 75 suitably-disposed peripheral stud 101 on a collar 102 fast on the shaft 69. Thus the dog 98 is raised and is so held until the shaft 69 is moved rearward and the disk is engaged with the rearward locking dog 76, as seen in 80 Fig. 10. At this stage the squared portion of the shaft is clear of the bearing 71. Hence the shaft 69 can be partially rotated by actuation of the handle 67 so as to raise the register controlling element, and position the 85 notch 800 of the disk 75 in register with the notch of the dog 76 preparatory to the act of pulling the carriage forward to deliver an article at the front of the machine.

In the initial turning of the shaft 69 the 90 stud 101 escapes the toe of the dog 98, whereupon the forward notched portion of the dog bears on the lateral stud 97 of the shaft 86, thus permitting such dog to engage the stud 97 and lock the shaft 86 with its latch arm 87, 95 in outer position when the crank lug 90 is actuated by the head of the dog 94 in the initial forward movement of the carriage, as will presently appear. (See Fig. 11.) In the initial forward movement of the carriage, 100 the squared portion of the shaft enters the opening of the bearing 71, thus preventing the rotative movement of the shaft and the descent of the register controlling element until the carriage has reached the limit of its 105 forward travel.

In this forward travel the lowermost carton of the stack rests upon the forward portion of the shelf plate 44, in front of the vertical member of the register controlling element, and therefore, such carton is positively advanced from the magazine to the exterior of the machine, whence it may be removed. (See Fig. 3.) As the carton descends upon the shelf plate the front end of the carton 115 bears against a depending rearwardly inclined arm 103 which is pivoted at its upper end, as at 104, to the carriage plate 390. The lower end of the arm is jointed to the horizontal latch-rod 92 previously referred to, which 120 rod is slidably supported adjacent its free end in lugs 204 on the carriage bar 400, and is urged rearwardly by means of a suitably-disposed spring 105 encircling the rod. (See Fig. 1.) In the absence of a carton on the 125 shelf the free end of the rod 92 is normally pressed toward and across the top of the crank-head 89, at one side thereof, so as to lie adjacent the inner face of the upstanding lug 91, as seen in Fig. 4, thus locking the crank- 130

head and its shaft 86 in a position with the latch arm 98 swung away from the depending leg 51 of the register controlling element. Hence when the projected carton is removed from the shelf the latch rod 92 is instantly moved rearward to lock the latch arm in its outer position. At this juncture the squared portion 70 of the shaft 69 is clear of the bracket 71, and the notched disk 75 thereon is engaged with the forward, locking dog 77. Consequently the carriage cannot be pushed rearward until the shaft 69 has been properly turned to effect the registry of the notch 800 of the disk with the notch of the dog 77. The turning of the shaft 69 and the cam wheel 63 by means of the handle 67, permits the descent of the register controlling element, and, consequently, of the stack of articles supported thereon until the lowermost article rests on the shelf bar, which article, bearing against the inclined yielding arm 103 when the carriage is pushed rearward, effects the unlocking of the crank head 89.

As the shaft 69 approaches the limit of its semirotation, the stud 101 of the collar 102 on such shaft passes under the toe 100 of the dog 98 and disengages the latter from the stud 97 of the shaft 86. This done, the carriage, with the register controlling element in down position, can be forcibly pushed rearwardly. As the carriage approaches the limit of its rearward travel, the lug 90 of the crank-head 89 passes under the latch head 93 of the dog 94 and the latch head drops in front of the lug. At the same time the carriage is locked in place in readiness for a succeeding forward delivery operation, as previously explained.

From the foregoing it will be seen that if any article delivered by the carriage be removed from and then replaced on the shelf 44, before the semi-rotation of the handle 67 to effect the unlocking of the carriage, such article upon its being returned to the shelf 44, will retract the locking rod 92 against the action of the spring 105, thus releasing the crank head. Upon such semi-rotation the stud 101 of the collar 102 will ride under the toe 100 of the dog 98, thus disengaging the latter from the stud 97 of the shaft 86; whereupon this shaft will be instantly moved by the action of the spring 88 to throw the latch arm 87 under the leg 51 of the register controlling element, thus retaining such element in raised position. This done, the carriage, with the elevated register controlling element and the returned carton, can be pushed rearward until the disk 75 on the shaft 69 engages and is locked by the rearward dog 76. In the rearward movement of the carriage the latch arm 87 remains under the elevated register controlling element and the latter supports the superposed stack of cartons in the magazine until the element escapes the stack, whereupon the returned car-

ton on the shelf 44 is brought under the stack.

The operation of releasing the carriage and pulling it forward is the same as previously described when the register controlling element is in down position, save that, owing to the unlocked condition of the crank head, the beveled corner 96 of the lug 90 when it impinges against the opposing surface of the latch head 93 of the dog 94 (during the initial forward movement of the carriage after the manual rotation of the shaft 69 has been effected) is forced laterally in a manner to shift the crank head on its axis, thus, partially turning the shaft 86 and swinging the latch arm 87 away from the leg 51 of the register controlling element. In this turning movement of the shaft 86 the stud 97 on its lower part moves into position to be engaged by the dog 98, thereby locking the latch arm in outward position against the action of the spring 88. At this juncture as the forward motion of the carriage is continued the squared portion 70 of the shaft 69 is entered in the bearing 71, and hence the register controlling element is maintained in its elevated position until it completes the forward delivery stroke. If the article then be removed from the shelf plate 44, (and not returned) the latch rod will engage the lug 91 of the crank head 89 and lock the latch arm in its outer position, so that when the handle is again properly actuated, preparatory to the next succeeding inward movement of the carriage, the register controlling element will be lowered, as previously described.

A counter or registering device R of any usual or approved type is conveniently supported at the front of the machine and is adapted to be operated by and during each succeeding inward or rearward travel of the carriage, when and only when an article has been removed from the shelf 44 and has not been returned thereto, thus consecutively indicating or registering the number of articles which have been delivered and actually taken away. In the present instance the usual unit shaft 106 of the counter or register is provided at one end with a crank 107 having a pin and slot connection 108 with the depending arm 109 of a crank lever which is actuated to oscillate the crank and shaft 106 at proper intervals.

This operating lever is maintained in its primed or set position against the action of a suitably-disposed spring 110, by means of a latch comprising an angle arm 111 fast on a rock-shaft 112 which is journaled in a bracket 113 on a forward extension 114 of the base bar 37. The upper end of the latch arm extends freely through a slot in the base and is formed with a recessed portion 115 which engages the free end of the horizontal arm 116 of the crank lever in a manner to hold it in raised position against the action of the spring 110. (See Fig. 19). The latch

arm is held normally in locking relation to the lever arm 116 by means of a suitable spring 117 which exerts upward pressure on a rearwardly extending lever arm 118 fast on the rock-shaft 112. The free end of the arm 118 is jointed to the lower end of a vertical plunger 119 which is slidable in a bearing on the extension 114, the head of the plunger being directly in the vertical path of the leg 51 of the register controlling element when the latter is lowered at the front of the machine as previously described. Hence when the register controlling element descends, preparatory to its rearward travel 15 after the delivery and permanent removal of an article from the machine, the leg 51 impinges against and forcibly depresses the plunger 119, as seen in Fig. 20, thereby correspondingly moving the lever arm 118 and, 20 perforce, swinging the latch arm 111 from the lever arm 116, thus priming or setting the unit shaft preparatory to a registering operation. When the leg 51, in the rearward travel of the carriage, escapes the plunger 25 119 the plunger is moved upward and the arm 111 is swung forward by the reaction of the spring 117, as seen in Fig. 21.

A rearwardly extending finger 190 affixed to the front portion of the carriage constitutes a simple form of register actuating mechanism. This finger is constructed and arranged to pass under and bear against a lateral roll 120 on the upper arm 116 of the operating lever as the carriage approaches the limit of its rearward travel, thereby raising the arm 116 to a position where the latch arm 111 snaps into engagement with the opposing end of the arm 116, as seen in Fig. 22. Coincidentally, the unit shaft 106 of the register 30 is actuated to effect the requisite step of the number or indicating element of the register, thus ensuring the positive checking of each article which has been actually removed from the machine. When the carriage 35 is pulled forward or outward to deliver an article the finger 190 is distant from the roll 120, and hence the registering devices are in proper condition for a succeeding operation when the register controlling element is 40 next lowered at the front of the machine.

The machine may embody any suitable signaling device, aural or visual, which is automatically actuated when the mechanism is manually operated to deliver an article. In 45 the present instance a bell is arranged and adapted to be sounded when the carriage is being pulled outward. The body 121 of the bell is suitably mounted at the back of the frame structure adjacent the base, and the clapper lever 122 therefor is fulcrumed to the base bar 37 of the stationary frame, a suitably-disposed spring 123 maintaining the acting end of the lever normally in contact with the bell body. The vertically movable operating pin 124 for the lever is guided in an

aperture in the bar 37 and is provided at its upper end with a bevelled head 125 upon which idly rides a by-pass pawl 126 on the depending bracket 68 of the carriage when the carriage approaches the limit of its rearward travel. In the initial forward movement of the carriage the pawl 126 bears upon the inclined head 125 and depresses it, thus swinging the acting end of the clapper lever away from the bell body against the action of the spring 123. Hence when the pawl escapes the head 125 the latter is free, and, consequently, the spring snaps the clapper lever sharply against the bell body, thus sounding the bell. (See Figs. 1, 2, 3 and 4.)

As a simple and efficient means to indicate the depletion, or near depletion, of the contents of a magazine, we mount in bearings 127 on one of the front side bars 28 of each magazine, a vertical rock-shaft 128 to which is affixed, at a suitable height from the shelf 44, a plate 129, bearing a suitable notice, as, for example, "Restock", which may be swung toward and from the front of the magazine. A torsional spring 130 encircling the shaft 128 and having one end secured to the adjacent bearing and the other end pressing against the sign plate tends normally to swing the plate to an exposed position across the front of the magazine. When the stack of cartons extends to or above the sign plate, the carton contiguous thereto holds the plate in retracted hidden position against the action of the spring 130, but when the uppermost carton descends below and escapes the plate, the latter, being unrestrained, is swung forward by the spring. The lower end of the shaft 128 is preferably provided with an electric contact foot 131 which, when the sign plate is swung forward, electrically connects the broken contacts 132 of an electric circuit 133, in which an electric bell 134, or other signaling device, is included at any convenient location, thus completing the circuit and giving a suitable signal to indicate that the contents of the magazine should be replenished. (See Figs. 9 and 18.)

It is to be understood that our invention is not limited to the exemplifying embodiment thereof herein disclosed, as the mechanisms may be modified within the principle of the invention and the scope of the appended claims.

We claim—

1. In an article dispensing apparatus, the combination with means for successively supplying articles, of article delivery mechanism movable to article receiving and delivering positions, means for locking and unlocking said delivery mechanism in its delivery position, a registering mechanism, and means associated with said delivery mechanism for effecting the operation of said registering mechanism when an article is delivered by and removed from the delivery mechanism,

- 5 said last-named means including an element which is movable into co-operative relation to the registering mechanism during the unlocking of the delivery mechanism when the delivery mechanism is in delivering position. 70
- 6 2. In an article dispensing apparatus, the combination with means for successively supplying articles, of article delivery mechanism movable to article receiving and delivering positions, a registering mechanism, and means associated with said delivery mechanism for effecting the operation of said registering mechanism when an article is delivered by and removed from the delivery mechanism, 75
- 10 15 said last-named means including an element which is movable into co-operative relation to the registering mechanism when the delivery mechanism is in delivering position, and including also latching devices which are maintained in disengaging relation to said element by an article borne on the delivery mechanism. 80
- 15 20 3. In an article dispensing apparatus, the combination with means for successively supplying articles, of article delivery mechanism movable to article receiving and delivering positions, means for locking and unlocking said delivery mechanism in both positions, a registering mechanism, and means associated with the delivery mechanism for effecting the operation of said registering mechanism, said last-named means including an element which is movable into co-operative relation to the registering mechanism during the unlocking of the delivery mechanism when the latter mechanism is in delivering position. 85
- 20 25 35 4. In an article dispensing apparatus, the combination with means for successively supplying articles, of article delivery mechanism movable to article receiving and delivering positions, means for locking and unlocking said delivery mechanism in both positions; a registering mechanism, and means associated with the delivery mechanism for effecting the operation of said registering mechanism, said last-named means including an element which is movable into co-operative relation to the registering mechanism during the unlocking of the delivery mechanism when the latter mechanism is in delivering position. 90
- 25 30 35 40 45 50 55 60 65 70 75 80 85 90 95 100 105 110 115 120 125 130
5. In an article dispensing apparatus, the combination with a magazine, of article delivery mechanism, including a support for the lowermost article contained in the magazine, a register controlling element vertically movable with respect to said support, said element having an elongated top portion constructed and arranged to pass under and sustain the contents of the magazine during the delivery operation of said mechanism, means for locking and unlocking said delivery mechanism in article receiving and delivering positions, means for operating said element during the unlocking operation in the article delivering position, and a registering mechanism actuatable during the movement of the delivery mechanism from delivering to receiving position, said registering mechanism including a member which is operable by the lowering of the controlling element when the delivery mechanism is in delivering position. 75
6. In an article dispensing apparatus, the combination with a magazine, of article delivery mechanism, including a support for the lowermost article contained in the magazine, a register controlling element vertically movable with respect to said support, said element having an elongated top portion constructed and arranged to pass under and sustain the contents of the magazine during the delivery operation of said mechanism, means for temporarily retaining the controlling element in raised position, said means including a latch device under the influence of an article borne on the delivery mechanism, means for locking and unlocking said delivery mechanism in article receiving and delivering positions, means for operating said element during the unlocking operation, and a registering mechanism actuatable during the movement of the delivery mechanism from delivering to receiving position, said registering mechanism including a member which is operable by the lowering of the said controlling element during the unlocking of the delivery mechanism when the latter mechanism is in delivering position. 90
7. In an article dispensing apparatus, the combination with means for successively supplying articles to be delivered of a delivery mechanism including an article support, a register controlling element, and a register actuating member, means for locking and unlocking said mechanism in receiving and delivering positions, including devices for independently operating the said element when an article is presented by and removed from the support, registering mechanism in co-operative relation to the said element and actuating member, and article-controlled means associated with said support to prevent the effective operation of said element when the support, with an article imposed thereon, is in delivering position. 105
8. In an article dispensing apparatus, the combination with means for successively supplying articles, of article delivery mechanism including a support for each succeeding article, and a register controlling element movable relatively to said support, manually-operative means for locking and unlocking said delivery mechanism in receiving and delivering positions, said means including devices for operating said controlling element during the unlocking of the delivery mechanism, and registering mechanism ar- 120
- 60 65 70 75 80 85 90 95 100 105 110 115 120 125 130

- ranged in co-operative relation to said delivery mechanism and including a member with which the said controlling element co-operates during the unlocking of the delivery mechanism in its delivering position. 70
9. In an article dispensing apparatus, the combination with means for successively supplying articles, of article delivery mechanism including a support for each succeeding article, and a register controlling element movable relatively to said support, manually-operative means for locking and unlocking said delivery mechanism in receiving and delivering positions, said means including devices for operating said controlling element during the unlocking of the delivery mechanism, means under the influence of an article on said support for temporarily maintaining the controlling element in ineffective 75
- 10 position during the unlocking of the delivery mechanism, and registering mechanism arranged in co-operative relation to said delivery mechanism and including a member with which the said controlling element co- 80
- 15 operates during the unlocking of the delivery mechanism in its delivering position when an article is removed from the support. 85
10. In an article dispensing apparatus, the combination with means for successively supplying articles, of article delivery mechanism including a support for each succeeding article, and a register controlling element vertically movable with respect to said 90
- 30 support, manually-operative means for locking and unlocking said delivery mechanism in receiving and delivering positions, said means including devices for operating said controlling element during the unlocking of the delivery mechanism, and including also devices for raising said element during the 95
- 35 unlocking of the delivery mechanism at one limit of its travel and for permitting the descent of said element during the unlocking of the delivery mechanism at the other limit of its travel, said last-named devices including a rotary shaft, a cam thereon, and operative connections between said cam and the controlling element, and registering mechanism arranged in co-operative relation to 100
- 40 said delivery mechanism and including a member with which the controlling element co-operates during its descent. 105
11. In an article dispensing apparatus, the combination, with means for successively supplying articles, of article delivery mechanism including a support for each succeeding article, and a register controlling element vertically movable with respect to said 110
- 45 support, manually-operative means for locking and unlocking said delivery mechanism in receiving and delivering positions, said means including devices for operating said controlling element during the unlocking of the delivery mechanism at the other limit of its travel, and registering mechanism arranged in co-operative relation to said delivery mechanism and including a member with which the controlling element co-operates 115
- 50 during its descent. 120
12. In an article dispensing apparatus, the combination with means for successively supplying articles, of a reciprocative carriage including a support for each succeeding article, a shaft mounted on and extending longitudinally of said carriage, manual means for reciprocating said carriage and rotating said shaft, locking and unlocking devices for said carriage at each limit of its movement, said devices including a member fast on and rotatable with said shaft, a register controlling element mounted on said carriage and movable relatively to the said support, and connections between said shaft and the controlling element whereby the said element is operable independently of the carriage during the unlocking of the carriage, and registering mechanism arranged in co-operative relation to the carriage and including a member with which the controlling element co-operates during the unlocking of the delivery mechanism in its delivering position. 125
13. In an article dispensing apparatus, the combination with means for successively supplying articles, of a reciprocative carriage including a support for each succeeding article, a shaft mounted on and extending longitudinally of said carriage, manual means for reciprocating said carriage and rotating said shaft, locking and unlocking devices for said carriage at each limit of its movement, said devices including a member fast on and rotatable with said shaft, a register controlling element mounted on said carriage and movable relatively to the said support, and connections between said shaft and the controlling element whereby the said element is operable independently of the carriage during the unlocking of the carriage, and registering mechanism arranged in co-operative relation to the carriage and including a member with which the controlling element co-operates during the unlocking of the delivery mechanism in its delivering position. 130
14. In an article dispensing apparatus, the combination with means for successively supplying articles, of a reciprocative carriage including a support for each succeeding article, a shaft mounted on and extending longitudinally of said carriage, manual means for reciprocating said carriage and rotating said shaft, locking and unlocking devices for said carriage at each limit of its movement, said devices including a member fast on and rotatable with said shaft, a register controlling element mounted on said carriage and movable relatively to the said support, and connections between said shaft and the controlling element whereby the said element is operable independently of the carriage during the unlocking of the carriage, and registering mechanism arranged in co-operative relation to the carriage and including a member with which the controlling element co-operates during the unlocking of the delivery mechanism in its delivering position. 135

ing article, a shaft mounted on and extending longitudinally of said carriage, manual means for reciprocating said carriage and rotating said shaft, locking and unlocking devices for said carriage at each limit of its movement, said devices including a member fast on and rotatable with said shaft, a register controlling element mounted on said carriage and movable relatively to the said support, and connections between said shaft and the controlling element whereby the said element is operable independently of the carriage during the unlocking of the carriage, means under the influence of an article on said support for temporarily maintaining the controlling element in idle position during the unlocking of the carriage, and registering mechanism arranged in co-operative relation to the carriage, and including a member with which the controlling element co-operates during the unlocking of the carriage when an article is delivered by and removed from the support.

15. In an article dispensing apparatus, the combination with means for successively supplying articles, of a reciprocative carriage including a support for each succeeding article, a shaft mounted on and extending longitudinally of said carriage, manual means for reciprocating said carriage and for rotating said shaft at each limit of its travel, means for preventing rotation of said shaft during its major traverse between said limits, locking and releasing devices for said carriage at each limit of its travel, a vertically movable register controlling element mounted on said carriage, connections between said shaft and the controlling element whereby the said element is operable independently of the carriage during the unlocking of the carriage, means, under the influence of an article on said support for temporarily maintaining the controlling element in raised position during the unlocking of the carriage, said last-named means including a latch member normally urged into engaging relation to the elevated controlling element, and devices operable by an article on said support for locking said latch member in disengaging relation to the controlling element, and registering mechanism arranged in co-operative relation to the carriage and including a member with which the controlling element co-operates during the unlocking of the carriage when an article is delivered by and removed from the support.

16. In an article dispensing apparatus, the combination with a magazine, of article delivery mechanism including a support for the lowermost article contained in the magazine, and means for actuating said mechanism and locking and unlocking it in receiving and delivering positions with respect to the magazine, said means including a manually-operative member, and locking devices operative automatically to lock the delivery mechanism at each limit of its movement, but manually operative to unlock said mechanism at either limit and simultaneously position the devices for automatically lock-

ing said mechanism at the succeeding limit of movement, a registering mechanism in co-operative relation to said delivery mechanism, an independently movable register control element on said delivery mechanism, means including connections between said manually operative member and said element, for actuating said element at the respective positions of the delivery mechanism, a latch device for said element, and means under the influence of an article borne on the support for maintaining said device in disengaging relation to said element.

17. In an article dispensing apparatus, the combination with means for successively supplying articles, of a reciprocative carriage including a support for each succeeding article, a shaft mounted on and extending longitudinally of said carriage, manual means for reciprocating said carriage and for rotating said shaft at each limit of its travel, means for preventing rotation of said shaft during its major traverse between said limits, locking and releasing devices for said carriage at each limit of its travel, a vertically movable register controlling element mounted on said carriage, connections between said shaft and the controlling element whereby the said element is operable independently of the carriage during the unlocking of the carriage, means, under the influence of an article on said support for temporarily maintaining the controlling element in raised position during the unlocking of the carriage, said last-named means including a latch member normally urged into engaging relation to the elevated controlling element, and devices operable by an article on said support for locking said latch member in disengaging relation to the controlling element, and registering mechanism arranged in co-operative relation to the carriage and including a member with which the controlling element co-operates during the unlocking of the carriage when an article is delivered by and removed from the support.

18. In an article dispensing apparatus, the combination with means for successively supplying articles, of a reciprocative carriage including a support for each succeeding article, a shaft mounted on and extending longitudinally of said carriage, manual means for reciprocating said carriage and also for rotating said shaft at each limit of its travel, means for preventing rotation of said shaft during its major traverse between said limits, locking and releasing devices for said carriage at each limit of its travel, a vertically movable register controlling element mounted on said carriage, connections between said shaft and the controlling element whereby the said element is operable independently of the carriage during the unlocking of the carriage, means under the influence of an article on said support for

- temporarily maintaining the controlling element in raised position, said last-named means including a latch member normally urged into engaging relation to the elevated controlling element, a rock shaft for said latch member, a crank-head on said rock shaft, a lock member for the crank-head, means adjacent the article support operable by the presence of an article thereon to maintain the lock member in idle position, a stud on the rock shaft, a dog on the carriage with which said stud is engaged at the rearward position of the carriage, means on the shaft for moving said dog and disengaging it from the stud during the act of unlocking the carriage when the carriage is in its forward position, means for actuating the crank-head to release the latch member from the controlling element during its initial forward or delivery stroke, and registering mechanism arranged in co-operative relation to the carriage and including a member with which the controlling element co-operates during the unlocking of the carriage at the limit of its forward movement when an article is delivered by and removed from the support.

Signed at Jersey City, in the county of Hudson and State of New Jersey, this 25th day of June, A. D. 1929.
